BOUDOIR AND TABLE LAMP

Eugene Schwarz, Alexandria, Ind., assignor to
The Mantle Lamp Company of America, Chi-
cago, Ill., a corporation of Illinois

Application October 1, 1938, Serial No. 232,753

3 Claims. (Cl. 240—81)

My invention consists of a cast or pressed glass lamp stand including as an integral and unitary structure, a hollow base, a slender column and a head for supporting a lamp socket, which structure is adapted for use for any purpose where small portable electric lamps are desired, such, for example, as boudoir and small table lamps, and particularly where it is desired that such lamps shall be decorative.

10 Heretofore, in connection with lamp stands of the kind under consideration, several practices have been followed: first, the electric conductors connected with the lamp socket have been permitted to emerge from the lamp stand immediately 15 below the lamp socket and hang loosely from that point according to the connection of the conductors to supply the lamp with current; second, the lamp stand has been constructed of separate pieces, for example, a base and a glass tube or stem, held together by a pipe usually 20 of metal extending through the glass tube or stem and the base to contain the conductors and to hold the parts together, and usually serving also as a supporting connection for the lamp 25 socket; and third, the lamp stand including the base and tubular stem have been made in one integral piece by a blowing or by a press and blow operation.

The first practice referred to is open to the 30 objection that exposed electrical conductors are unsightly and readily become tangled and engaged with objects surrounding the lamp stand; the objection to the second practice is that the cost of construction of the lamp stand is relatively large, and furthermore, decorative effects 35 that may be desired cannot readily be secured; and the objection to the third practice is that the tubular stem must be so large laterally of the stem, as to be clumsy and unsightly for small 40 lamp stands.

By my invention I overcome the objections to the practices referred to, by constructing the lamp stand as an integral and unitary pressed glass structure including a hollow base and a slender column extending upwardly from the base and provided at its upper end with a head which is 45 preferably threaded to engage similar threads on a supporting and connecting member to which the lamp socket is secured. The electric conductors extending from the lamp socket are concealed by being contained in a groove in the surface of the slender column and which extends lengthwise of the column and preferably in its 50 back surface in use, and from the lower end of said groove the conductors extend through an

aperture in the top wall of the base which is adjacent to said groove, thus leading the conductors into the hollow base from which they pass through an aperture in its side wall and continue to any desired point to supply the lamp 5 socket with current. In this manner the electric conductors are contained within the lamp stand without requiring the column to be tubular. It is to be understood that with slender columns of the kind under consideration, the 10 columns cannot be made hollow by casting or pressing operations, unless they are of much larger cross section than is permissible in producing slender columns of the kind referred to.

In describing the lamp stand as being made 15 of pressed glass I include within the meaning of that term any casting or molding operation by which the molten glass is given the desired form in a mold having the conformation of the finished lamp stand, whether the molding is effected by 20 mechanical pressure, by blowing, as by air under pressure, or in any other way, the mold being so constructed that the base, the slender column and the head of the lamp stand are constructed as a single integral and unitary glass structure, 25 by a single operation, the apertures in the base being formed in any convenient manner in connection with the molding operation, for example, by employing removable plugs in the mold.

In constructing the lamp stand in accordance 30 with my invention, I prefer to use clear or crystal glass on account of its decorative effects due to the refraction of light rays passing through it; and to obscure the electric conductors in the longitudinal groove in the back surface of the 35 slender column, I preferably provide the front and sides of the slender column with lens surfaces which so diffuse and disperse light rays projected from the electrical conductors through the clear glass of the column, that the outlines 40 and detail of the electrical conductors are obscured to such a degree that said conductors are substantially invisible from the front and sides of the lamp stand. The lens surfaces referred to may conveniently be cylindrical lens surfaces 45 on the sides of the lamp stand and a series of spherical lens surfaces on the front of the slender column as below described, which lens surfaces besides effectively concealing the electrical conductors although the material of the lamp stand is clear and transparent glass, also produce pleasing decorative effects which may be supplemented by any other desired ornamental shapes applied purely for decorative purposes. The electrical conductors are preferably permanently secured 50

in the longitudinal groove in the back surface of the slender column by suitable cement so that they will stay in place and not interfere in any way with the handling of the lamp stand.

5 My invention will be best understood by reference to the accompanying drawing illustrating a preferred embodiment thereof, in which—

Fig. 1 shows my improved lamp in a front elevation,

10 Fig. 2 is a side elevation of the lamp stand shown in Fig. 1, with the lamp socket and mounting member removed.

Fig. 3 is a back view of the structure shown in Fig. 2,

15 Fig. 4 is a top view to an enlarged scale of the structure shown in Fig. 3.

Fig. 5 is a horizontal sectional view to an enlarged scale, through the structure shown in Fig. 1 taken along the line 5—5 of that figure, and

20 Fig. 6 is a vertical, central, sectional view to an enlarged scale, through the lower part of the lamp socket and mounting member.

Similar numerals refer to similar parts throughout the several views.

25 As shown in Fig. 1, my lamp construction consists of a base 10 from which a slender column 11 extends upwardly, said column having at its upper end a head 12 having threaded engagement with an annular connecting member 13 which

30 supports a lamp socket 14 above the column 11. The base 10, slender column 11, and head 12, are an integral and unitary pressed glass structure made preferably of clear or crystal glass which may either be colored or uncolored as desired.

35 While I do not limit myself specifically to any particular sizes of the parts, the meaning of the term "slender column" as used herein may be illustrated by one practical construction of the invention in which the column is from 8" to 10" high and has an over-all diameter of about 3/4".

40 As indicated in Fig. 4, the base 10 is hollow at 10a, being provided with a side wall 10b, through which an aperture 10c is formed to receive electrical conductors 15 as illustrated in

45 Figs. 2 and 3. As also illustrated in Fig. 4, a second aperture 10d is formed through the top wall of the base 10 adjacent to the lower end of a longitudinal groove 11a formed in the back surface of the slender column 11, which groove 11a

50 extends from top to bottom of the column 11 and also through the head 12 at the upper end of said column. With this arrangement of the apertures 10c and 10d and groove 11a, the electrical conductors 15 in the completed lamp, pass through the apertures 10c and 10d and upwardly in groove 11a to the lamp socket 14, the groove being of sufficient size to entirely contain and conceal the electric conductors 15 as shown in Fig. 5.

55 As shown in Figs. 2 and 3, the upper end of the head 12 is preferably provided with screw threads 12a to receive similar screw threads on the lower end of the connecting member 13 shown in Fig. 1, to support the lamp socket 14.

60 In assembling the parts of the complete lamp, the electric conductors 15 are first mounted in the base and column 11 as described and as illustrated in Figs. 2 and 3, this mounting of the conductors being readily accomplished in the column 11, because of the groove 11a continuing through the head 12 as well as through the screw threads 12a formed on the upper end of said head. The groove 11a is preferably somewhat deeper in the head 12, as illustrated at 11b in Fig. 4, than it is in the column 11 below the head 12, so that the electric conductors 15 may be centered

on emerging from the head to facilitate extending said conductors through the mounting member 13 into the lamp socket 14. The electric conductors are preferably held in the groove 11a by suitable cement such as, for example, water glass. To complete the assembly of the lamp, the supporting member 13 is threaded over the upper ends of the electrical conductors 15 and tightly screwed in place on the threads 12a of the head 12, said supporting member 13 preferably having rigidly secured to it the lower separable portion of the lamp socket 14. The electrical conductors are then connected to the terminals of the lamp socket in the usual manner, and the portions of the lamp socket are put together in operative relation and the assembly of the lamp is complete.

It will be noted that the screwing of the mounting member 13 on the threads 12a, provides a retaining member around the conductors 15 in the upper portion of the head 12, so that with the supporting member 13 screwed on the head 12, said conductors cannot be moved from the upper end 11b of the groove 11a.

As shown in Fig. 6, the mounting member 13 may be conveniently and rigidly secured to the socket 14, by means of an externally threaded and flanged sleeve 13a extending through the member 13 and tightly screwed into internal threads in the ferrule 14a constituting the mounting support of the socket 14.

As a result of the construction described, it will be noted that the electrical conductors 15 are entirely concealed from view when looking at the sides of the lamp stand as illustrated in Fig. 35. 2. In front elevation, however, on account of the clear and transparent nature of the glass of which the lamp stand may be made, the electrical conductors would be clearly visible through the material of the column 11, were some suitable 40 means not provided to obscure the outlines of said conductors and make them practically invisible from the front of the lamp stand. The construction accomplishing the obscuring of the visibility of said conductors is an important part 45 of the present invention and consists essentially of providing the column 11 with lens surfaces 11e, 11f and 11g, the lens surfaces 11e and 11f as illustrated being cylindrical surfaces extending longitudinally of the column along its sides, and the lens surfaces 11g as illustrated comprising a series of spherical lens surfaces arranged vertically on the front surface of the column so that they are closely adjacent to each other.

50 Besides imparting an ornamental appearance to the lamp stand, said lens surfaces have a pronounced optical effect on the visibility of the electrical conductors 15 through the material of the column 11, as more clearly illustrated in Fig. 5. As shown in that figure, rays of light 16 60 are shown projected from one edge of the conductors 15 through the glass of the column 11 and through the cylindrical lens surface 11f thereof, which lens surface, being convex, has the effect of materially dispersing said rays 16 as 65 they emerge from said lens surface. A similar effect is of course produced on light rays projected from any other portion of the conductors 15 through the glass of the column 11 and through the convex lens surface 11f. Similarly, light rays 70 17 projected from one edge portion of the conductors 15 through the glass of the column 11 and through the convex and cylindrical lens surface 11e are also dispersed and the light rays projected from other portions of the conductors 75

15 through the lens surface IIe are similarly dispersed with the effect of substantially obscuring the view of the conductors through the lens surface IIe . Furthermore, light rays 18 projected from the edges of the conductors 15 as illustrated in Fig. 5, through one of the spherical lenses IIg are dispersed by said lens surface which is convex, with the effect of obscuring the detail of the conductors 15 as viewed through the lens 10 IIg . In connection with the lens IIg , it will be noted also that a similar dispersive effect on rays projected from the conductors 15 through said lens, is produced vertically on rays passing through different vertical locations on said lens surface. The combined action of the lens surfaces IIe , IIf and IIg on light rays projected through the column II from the conductors 15 , is therefore to so diffuse and disperse said rays that visibility of the detail of the conductors 15 15 through the column II is practically zero, whether the observer be in front of or on either side of the lamp stand. Each of the spherical lenses IIg of course has an effect of the kind described, on the light rays projected through it from the 20 conductors 15 , and although the cylindrical lenses IIe and IIf do not produce vertical dispersion or diffusion of the light rays projected from conductors 15 , horizontal diffusion of said rays is sufficient to so obscure the detail of the conductors 15 as to make them practically invisible 25 through the lenses IIe and IIf . It will be understood that the lens surfaces IIe , IIf and IIg need not be convex surfaces to produce an equivalent of the ray diffusion described, since any 30 form of lens surfaces may be employed that will so obscure the detail of the conductors 15 that they are not readily visible through the glass of the column II .

In addition to the lens surfaces referred to, the 35 column II may be provided with any desired forms of integral ornamentation as illustrated at 19 and 20 , and the base 10 may have any other form than that illustrated that will afford a stable support for the column II , the only requisite in 40 this connection, for economical production, being that whatever conformation may be given to the various portions of the integral glass structure, the latter may be readily removed from the mold in which the structure is formed. Another advantage resulting from forming the lamp stands in metal molds as described, is that by giving the mold surfaces a smooth finish throughout, the resulting molded structures of glass will have a high degree of polish making it unnecessary 45 to resort to further operations to finish the lamp stands. In some cases it may be desired to produce lamp stands of the kind described, of other kinds of glass than that referred to, and I do not therefore limit myself to any particular kind of 50 glass in carrying out my invention. It will be observed, however, that with clear and transparent glass, the optical effects of the lens surfaces described are particularly effective and important 55 as to light rays passing through the column, in

a manner that is not the case where the glass is not transparent.

While I have shown my invention in the particular embodiments above described, I do not limit myself thereto as I may employ equivalents 5 thereof without departing from the scope of the appended claims.

Having thus described my invention, what I claim is:

1. A one-piece mold-finished pressed glass supporting structure for electric lamps, including a base having a lower molded recess, a straight slender and solid column continuing and extending vertically from said base, and a socket-supporting head continuing and extending vertically from said column, said column having similar front and back grooves formed in its surface and extending longitudinally thereof from said base 20 for the reception of electrical conductors and said front groove containing small lenticular projections whereby the cross-section of said column is substantially symmetrical around the vertical axis of said column, and said base having molded apertures laterally and vertically through it for 25 the reception of electrical conductors.

2. A one-piece mold-finished pressed glass supporting structure for electric lamps, including a base having a lower molded recess, a straight slender and solid column continuing and extending vertically from said base, and a socket-supporting head continuing and extending vertically from said column, said column having similar front and back grooves formed in its surface and extending longitudinally thereof from said base 30 to said head, said back groove being for the reception of electrical conductors and said front groove containing small lenticular projections whereby the cross-section of said column is substantially symmetrical around the vertical axis 35 of said column, and said base having molded apertures laterally and vertically through it for the reception of electrical conductors, said back groove continuing and opening laterally through said head.

3. A one-piece mold-finished pressed glass supporting structure for electric lamps, including a base having a lower molded recess, a straight slender and solid column continuing and extending vertically from said base, and a socket-supporting head continuing and extending vertically from said column, said column having similar front and back grooves formed in its surface and extending longitudinally thereof from said base 40 to said head, said back groove being for the reception of electrical conductors and said front groove containing small lenticular projections 45 whereby the cross-section of said column is substantially symmetrical around the vertical axis of said column, and said base having molded apertures laterally and vertically through it for the 50 reception of electrical conductors, said column having a length of at least eight times its over-all diameter.

EUGENE SCHWARZ. 65
